UNITED STATES PATENT OFFICE.

LOUIS DOSCH, OF BROOKLYN, NEW YORK.

GAME-TABLE.

1,080,427.

Specification of Letters Patent.

Patented Dec. 2, 1913.

Application filed January 27, 1913. Serial No. 744,483.

To all whom it may concern:

Be it known that I, LOUIS DOSCH, a subject of the Emperor of Germany, residing at Brooklyn, in the county of Kings and State 5 of New York, have invented new and useful Improvements in Game-Tables, of which the following is a specification.

The general object of the invention is to improve the general character and efficiency 10 of game tables, such as are used in the games of shuffle-board, ten-pins and the like. And to this end the invention resides in surrounding the table proper with a frame, one of whose functions is to prevent the table from 15 being jarred or swayed upon persons leaning against the device while the balls, disks or other objects forming part of the game, are in motion on the surface of the table.

Other objects will appear and be better 20 understood from that embodiment of my invention of which the following is a specification, reference being had to the accompanying drawings forming a part hereof, in which:—

25 Figure 1 is a perspective of the device. Fig. 2 is a contracted vertical longitudinal section of the same. Fig. 3 is a section on the line 3—3 of Fig. 2. Fig. 4 is a section on the line 4—4 of Fig. 3. Fig. 5 is a detail 30 perspective showing an attachment for adapting the table to be used as a shuffle board. Fig. 6 is a detail perspective of a disk used in connection with the attachment shown in Fig. 5. Fig. 7 is a detail perspective of the playing stick or cue.

The frame indicated generally by *a* may 40 be formed of any material found suitable for the purpose, as wood and of any convenient length. The legs 5—5 which support the table a suitable distance above the floor, are by preference arranged on the opposite sides 6—6 of the table, those on each side being disposed suitable distances apart. Struts or cross pieces 7—7 connect opposite legs 5—5 45 with the opposite sides 6—6 of the frame; the presence of these elements lends an element of rigidity to the frame when the same is set up as shown in the drawings.

At one end of the frame *a* is a tapered 50 pocket 8 which forms the bottom of a compartment 9 whose sides 10 and 11 are connected to the sides 6—6 of the frame *a*, the said sides 10 and 11 rising for a considerable distance above the table and being connected 55 at their upper ends by a suitable cross beam

12. Suitable supporting legs are connected to the sides of the compartment and serve to support the structure as shown.

The table proper indicated generally by *b*, is arranged wholly within the frame *a* its 60 top 13 being, if so desired, covered with billiard cloth 14 and supported by the legs 15—15 which have flared bases 16—16 which provide relatively large bearing surfaces.

Referring now to Figs. 2, 3 and 4, the 65 sides 17—17 of the table are out of contact with the inturned portions 18—18 of the sides 6—6. So too is one end of the table spaced from the front end 19 of the frame 70 *a* while the rear end portion of the table extends well over the pocket 8 but is spaced 75 from the sides and the door 20 which forms the rear end of the compartment 9. With this construction it will be seen that even a considerable amount of vibration in the 80 frame will have no effect on the table. The table is so proportioned as to have its top *b* considerably above the inturned portions 85 18—18 but a trifle below the upper edges of the sides 6—6 and to have its sides 17—17 spaced from the portions 18—18 for a distance less than the diameter of the ordinary 90 pool ball 21. This construction admits of the sides 17 coöperating with the sides 6 and the inturned portions 18 to provide channels 95 or ways for the balls which roll laterally from the table. The interiors of the pocket 8 and compartment 9 are padded as indicated by 22 which padding deadens the sound resulting from the balls or pins 23 100 striking the sides of the compartment and walls of the pocket. Upon opening the door 20 access may be had to the compartment 9 and pocket 8, whereby to facilitate the setting up of the pins 23 and obtaining the 105 balls which fall into the pocket. A chute or return 24 has one end connected to the cross beam 12 and its opposite end directed into the front part of one of the ball-ways or channels and near a pocket 25 formed by 110 a strip of flexible material 26 connected to the front end 19 of the frame and adjacent end of the table. With this construction the balls upon being taken from the pocket 8 may be readily returned to the player occupying a position at the front end of the frame.

The device shown in Figs. 1 to 4 inclusive, is used in connection with the ordinary game of ten-pins, where the balls are driven 115

2

to the pins through the agency of a cue in the hands of a player. In Fig. 5, however, an attachment is shown for adapting the table for a modified form of game, such as 5 shuffle board. Here an attachment 27 having a plurality of pockets 28 is detachably connected to the rear end of the table by thumb screws 29 which pass through arms on the side of the attachment, one of such 10 arms being shown in Fig. 5 and indicated by 30. The attachment may be so formed as to have the mouths of the pockets in any relation to the long axis of the top 13, such as in the arrangement shown, where the mouths 15 of three of the pockets are directed longitudinally of the top, while the mouths of the end pockets are directed laterally of the top. With this construction the operator is required to direct either directly with his 20 hand or through the agency of a cue 31, a disk such as is indicated at 32, from the front end of the table into one of the pockets 28.

What is claimed as new is:

- 25 1. In a device of the class described, the combination of a frame, a table arranged within the frame and having the sides and ends of its top spaced from the corresponding parts of the frame, and a pocket at 30 one end of the frame and below one end of the table top.
2. In a device of the class described, the combination of a frame, having at one end 35 a pocket and a compartment communicating with the pocket and located thereabove and opening into the frame, a table wholly arranged within the frame and having the sides and one end of its top arranged in 40 spaced relation to the sides and one end of the frame and the other end of its top ex-

tending into the compartment and overlying the pocket.

3. In a device of the class described, the combination of a frame having at one end 45 a compartment and a pocket communicating with and located below the compartment and further having inturned extensions on its sides, a table located wholly within the frame and having one end extending into the compartment and overlying the pocket 50 and having its opposite sides arranged in spaced relation to the inturned extensions of the frame.

4. In a device of the class described, the combination of a frame having at one end 55 a compartment and a pocket communicating with and located below the compartment and further having inturned extensions on its sides, a table located wholly within the frame and having one end extending into 60 the compartment and overlying the pocket and having its opposite sides arranged in spaced relation to the inturned extensions of the frame, and a return extending from the compartment into the space between one 65 side of the table and the adjacent side of the frame.

5. In a device of the class described, the combination of a frame, a table wholly arranged within the frame and having its 70 sides and ends spaced from the corresponding portions of the frame and a flexible wall connecting one end of the pocket with the frame.

In testimony whereof I affix my signature 75 in presence of two witnesses.

LOUIS DOSCH.
